UNITED STATES PATENT OFFICE

CLIFFORD E. HARRISON, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA

TWO-PIECE RAM-BOX CAP

Application filed May 4, 1925. Serial No. 27,899.

My invention relates to furnaces having particular relation to stoker ram-box caps.

One object of my invention is to provide a two-piece ram-box cap, whereby the part most subject to deterioration through the action of the furnace heat may be readily removed and replaced with a minimum expenditure of time, labor and materials.

Other objects and applications of my invention, as well as details of construction and arrangement, whereby my invention may be practiced will appear more fully hereinafter, when taken in connection with the accompanying drawings, wherein

Fig. 1 is a perspective view of the front end of a furnace, illustrating the front section of the ram-box cap in position, and the rear extension in the act of being placed in position;

Fig. 2 is a longitudinal sectional view of the two-piece ram-box cap shown in Fig. 1;

Fig. 3 is a top plan view of the front base section;

Figs. 4 and 5 are transverse sectional views taken on the lines IV—IV and V—V, respectively, of Fig. 3; and

Figs. 6 and 7 are top plan and front end elevational views, respectively, of the ram-box cap extension shown in Figs. 1 and 2.

In Fig. 1 of the drawings is shown a front end portion 1 of a furnace comprising a front wall 2 and a plurality of rows of tuyere plates 3 alternating with retorts 4. Each retort 4 extends into a passageway 5 in the wall 2 through which the fuel may be fed by the usual ram mechanism (not shown).

The passageway 5 may comprise side walls 6 and 7 and a top wall 8. The furnace wall 2, of which a rear side 9 only is shown in

Fig. 1, may be constructed of brickwork.

In the practicable manufacture of furnaces, I have mounted the cap portion of a ram-box cap in the upper part of the fuel passage 5, whereby the contour of the upper part of the fire may be controlled and the fuel caused to pack in the mouth of the retorts 4 to a desired extent. Experience has shown, however, that the inner end only of the ram-box cap tends to deteriorate under the intense action of the fire, with the result that fre-

quent replacements of the whole ram-box cap are necessary. As will be apparent, such replacements necessitate the removal of a large amount of brickwork all of which must subsequently be replaced. Moreover, a large quantity of metal is necessarily wasted with the removal of each ram-box cap, since the inner end only is damaged. These undesirable results are overcome by my invention, experience having shown that repairs can be made in one-tenth the time originally required and with one-half the material. To this end, I provide a ram-box 10' with an elongated two-piece ram-box cap 10 which fits the upper portion of the furnace passage 5. The cap 10 comprises a front base section 11 and a rear section 12.

Referring to Figs. 1 to 5, inclusive, the base section 11 of the ram-box cap 10 comprises an inclined top wall 13, the opposite sides of which are extended downwardly to form side walls 14 and 15. Inner surfaces 16, 17, and 18 of the walls 13, 14, and 15, respectively, serve to guide the fuel as it passes through the passage 5 in the front wall 2. The base section 11 may be supported in the passage 5 by means of horizontal extensions 19 and 21 on the opposite sides of the inclined wall 13. A pair of supporting plates 22, constituting at least a part of a base portion 11' of the ram-box 10', are mounted in the front wall 2 on opposite sides of the passageway 5 so as to provide supporting shoulders 23 and 24 which respectively engage the horizontal extensions 19 and 21. The latter are provided with recesses 25 and 26 for the reception of locking lugs 27 and 28, respectively, said lugs being positioned on the supporting plates 22. A longitudinal movement of the base section 11 in the passage 5 is thus prevented.

A reinforcing wall 29 extends transversely of the base section 11 adjacent to a front end 31 thereof, and it is connected at its ends with side wall portions 32 and 33, which merge into the inclined wall section 13 adjacent to a rear end 34 of said base section. The latter end is provided with a transversely extending lug or shoulder 35 of wedge shape having beveled surfaces 36 and 37, for reasons as will presently appear. A plurality of ribs 38

serve to reinforce the upwardly extending shoulder 35.

Referring to Figs. 1, 2, 6, and 7, the rear ram-box cap section 12 embodying my invention may comprise side walls 39 and 41, the lower edges of which engage the supporting shoulders 23 and 24, respectively. An inclined top wall 42, which extends between the side walls 39 and 41, is contiguous to the inclined wall 13 of the base section 11, and it is so formed as to cause the fuel in the mouth of the retort 4 to be packed to the desired extent and the contour of the upper part of the fire flattened to meet the desired operating conditions. A front wall 43 is provided with a shoulder portion 44 having a recess 45 on the under side thereof. A surface 46 of the recess 45 is beveled complementarily to the surface 36 of the shoulder 35.

20 The recess 45 is adapted to receive the upwardly extending shoulder 35 when the parts are in the assembled position shown in Fig. 2, wherein it is noted that the complementarily beveled surfaces 36 and 46 are in engagement. The dimensions of the parts just mentioned are such that the rear cap section 12 may be unhooked from the base section 11 by raising the former a slight amount, say one-half inch. The cap section 12 may then 25 be entirely removed from the fuel passage 5. A reinforcing rib 47 extends rearwardly from the wall 43 parallel to the side walls 39 and 41 and intermediate the same.

As shown in Fig. 1, the dimensions of the 30 cap extension 12 are such that a single brick 48 is sufficient to close the portion of the fuel passage 5 immediately above the inner end of said cap extension.

When the inner end of the ram-box cap 35 deteriorates to such extent that replacement is advisable, it is only necessary to remove the brick 48 and thereafter raise the cap section 12, which represents the damaged portion, clear of the shoulder 35. The cap section 12 may then be removed from the fuel 40 passage 5 and replaced by a new cap section. A new brick 48 is now positioned over the inner end of the cap section 12 and the furnace is again in condition for operation.

45 While I have shown only one embodiment of my invention, for the purpose of describing the same and illustrating its principles of construction and operation, it is apparent that various changes and modifications may 50 be made therein without departing from the spirit of my invention. I desire, therefore, that only such limitations be imposed thereon as are indicated in the appended claims or as are demanded by the prior art.

55 60 I claim:

1. The combination with a furnace wall provided with a passage, of a ram-box for said passage comprising a base portion having shoulders and a ram-box cap mounted 65 on said shoulders, said cap comprising front

and rear sections, said rear section having side, top and end wall portions, said end wall portion being provided with a recess, of which one surface is bevelled, and said front section having an upstanding lug positioned in said recess in engagement with said bevelled surface. 70

2. The combination with a furnace wall provided with a passage, of a ram-box positioned in said passage comprising a base portion and a cap portion, said cap portion comprising front and rear sections, said front section having an inclined wall affording a fuel-deflecting surface, and extensions from said wall forming supporting shoulders 75 adapted to be mounted on said base portion, said front portion having an upstanding lug, and said rear portion having a recess for said lug, whereby said sections may be detachably interlocked. 80
